[57] CLAIM

The ornamental design for a resealable package, as shown and described.

DESCRIPTION

FIG. 1 is a top perspective view of a resealable package, according to our invention;

FIG. 2 is an elevational illustration of one end of the package, with the opposite end being a mirror image thereof;

FIG. 3 is a side elevational view of the package, with the opposite side being a mirror image thereof; and,

FIG. 4 is a bottom plan view thereof.
